UNITED STATES PATENT OFFICE.

JEAN B. DAUDELIN, OF FALL RIVER, MASSACHUSETTS.

SHUTTLE.

1,149,249.

Specification of Letters Patent. Patented Aug. 10, 1915.

Application filed March 23, 1915. Serial No. 16,461.

To all whom it may concern:

Be it known that I, JEAN B. DAUDELIN, citizen of the United States, residing at Fall River, county of Bristol, Commonwealth of Massachusetts, have invented certain new and useful Improvements in Shuttles, of which the following is a specification.

This invention relates to hand threading shuttles and particularly to a guard for the threading eye of such a shuttle to prevent dethreading during the run.

The present invention contemplates a combined eye guard and tensioning device made of a single length of material and adapted to direct the thread into the eye and to positively prevent improper escape of the thread therefrom while maintaining a uniform tension on it during the run of the shuttle.

The present device is adapted to be used in conjunction with a separate pin or post forming part of the tension element and located just behind said element, and past which the thread runs.

The construction and operation of my device will be more fully disclosed in the specification that follows.

In the drawings forming a part of that specification I have shown a thread guard which not only clearly illustrates the principles of my invention but is in itself a form found satisfactory in use and well adapted to the requirements of manufacture.

Throughout specification and drawings like reference numerals are correspondingly applied and in the drawings: Figure 1 is a plan view of the threading end of a shuttle equipped with my invention, the shuttle body being partially broken away for purposes of illustration. Fig. 2 is a side view thereof. Fig. 3 is a view of the thread guard removed from the shuttle, and Fig. 4 is a vertical section through the eye.

The shuttle body 1 may be of any construction having a bobbin chamber 2 in which is located a bobbin 3 on which is wound the thread T.

From the forward end of the bobbin chamber 2 leads the eye 4 to which the threading slots 5 and 6 connect. The slot 5 in the form shown is diagonally disposed with respect to the longitudinal axis of the shuttle and so sawed as to develop a curve on the shuttle top. The slot 6 connects the

slot 5 with the eye 4 and preferably enters said eye at a point near its top.

In order to facilitate entry of the thread into the slot 5 and to prevent dethreading of the shuttle by reason of the ballooning tendency of the thread during the run of the shuttle, a guide and guard member 12 of any desired type may overlie the slot 5. This device is preferably of the type shown in Patent #1,078,261.

The combined thread guard and tensioning device of the present invention consists of a single length of wire bent between its ends to form a thread tensioning device and so shaped at its delivery end as to guide the thread from the slot 6 into the eye 4 and to prevent escape of the thread back into said slot. The device consists of a shank 7 extending transversely across the shuttle and preferably disposed below the plane of entry of the threading slot 6 into the eye 4. The free end of the shank 7 is clenched into the wood of the shuttle to lock the guard in place.

The shank 7 at its opposite end is bent over upon itself to form a loop 8 substantially conforming to the contour of the delivery end of the eye 4. The free end of this loop is carried upwardly to a point above the plane of the shank 7 and slightly above the plane of entry of the slot 6 into the eye 4 but in spaced relation to said shank whereby to leave a passage between the overlapping portions of the loop through which the thread from the slot 6 may enter. Beyond the loop the shank extends transversely as a horizontal thread supporting portion 9 disposed slightly above the plane of the slot 6.

The thread supporting portion 9 terminates in a downwardly bent portion or turn located within the eye 5 between the point of entry of the slot 5 and the loop end 8 of the shank. Just beyond the turn 10, a pin 11 is driven into the wood of the shuttle. This pin serves as a guide post past which the thread is drawn and with the bend 10 provides a thread tensioning device. The shank 7 passes between the pin 11 and the exit end of the bobbin chamber and is bent around said pin and continues across the shuttle to the opposite side as a relatively straight portion. The thread from the bobbin chamber runs over a part 110 of this bar to the pin 11.

In use, the thread from the slot 6 is de-

flected by the upwardly extended portion of the loop 8 on to the thread supporting portion 9 from which it travels down the tensioning device between said bend 10 and the guide post 11 and is guided into the confines of the loop end by the overlapping portion of said loop. This portion in addition, prevents any tendency of the thread to escape back into the slot 6 by an upward movement. The shuttle is now threaded. The thread then feeds direct from the bobbin chamber, over that portion of the guard beyond the pin 11, around said pin, over the point where the shank portion is deflected from the bend 10 so as to pass around the pin, and finally out through the loop end 8 of the guard.

Various modifications in the form and construction of my device may obviously be resorted to within the limits of the appended claims.

What I therefore claim and desire to secure by Letters Patent is:

1. In combination with a shuttle having a thread delivery eye and a threading passage leading thereto, a thread guard and tensioning device comprising a shank having an end substantially conforming to the delivery end of said eye and having a downwardly deflected and rearwardly bent turn between said end and the point of entry of the thread into the threading passage, and a pin driven into the shuttle just behind the turn and in operative tension maintaining relation thereto and past which the thread from the bobbin runs.

2. In combination with a shuttle having

a thread delivery eye and a threading passage leading thereto, an eye guard and tensioning device comprising a shank having an end substantially conforming to the delivery end of said eye and having a downwardly deflected bend between said end and the point of entry of the thread into the threading passage, and a guide member driven into the shuttle just behind the bend and across which the thread from the bobbin runs, and providing with the bend a thread tensioning device, said shank beyond said downward bend being deflected rearwardly to pass between the guide member and the point of entry of the thread from the bobbin into said eye and over which the thread from the bobbin runs.

3. In combination with a shuttle having a delivery eye and a threading passage leading thereto, an eye guard and tensioning device comprising a shank set in said eye and having a thread supporting portion terminating in a downwardly bent turn, said turn carried rearwardly past and below the plane of entry of the thread from the bobbin into said eye and across which said thread runs, and a pin driven into the shuttle behind the downward bend and between the rearward bend and said plane of entry and in operative tension maintaining relation to said downward bend.

In testimony whereof I affix my signature in presence of two witnesses.

JEAN B. DAUDELIN.
